B. J. SHALD

ELECTRIC SIGNAL FOR RAILROAD CROSSINGS, PUBLIC HIGHWAYS, AND THE LIKE

Filed June 16, 1926

UNITED STATES PATENT OFFICE.

BRUCE J. SHALD, OF O'NEILL, NEBRASKA.

ELECTRIC SIGNAL FOR RAILROAD CROSSINGS, PUBLIC HIGHWAYS, AND THE LIKE.

Application filed June 16, 1926. Serial No. 116,427.

The invention relates to an electric signal for railroad crossings, public highways and the like.

The object of the present invention is to improve the construction of electric signals for railroad crossings, public highways and the like and to provide a simple, practical and efficient device of strong, durable and comparatively inexpensive construction adapted to be operated by the wheels of a train or other vehicle at a distance from a crossing or intersection and capable of displaying an illuminated signal or other electrically operated signaling means either visible or audible or both.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Fig. 1 is a longitudinal sectional view of an electric signaling device constructed in accordance with this invention, the signal being shown in elevation.

Fig. 2 is a transverse sectional view of the signaling device.

Fig. 3 is an enlarged detail longitudinal sectional view of the switch operating mechanism.

Fig. 4 is a plan view of the same.

In the accompanying drawing in which is illustrated the preferred embodiment of the invention 1 designates a visual signal designed to be arranged at a railroad crossing or intersection of a public highway or other place where it is desired to give warning of an approaching vehicle and consisting of a box or casing provided at opposite sides with transparent plates and which are covered by an opaque plate or member 2 having cut therein the word "Stop" or other warning. The casing may be of any desired construction and is designed to contain a pair of electric lamps 3 which are connected by independent circuits with operating devices located at opposite sides of the crossing or intersection and adapted to be operated by the wheels of a train or other

vehicle for closing a lamp circuit and causing one of the other of the said lamps 3 to glow and illuminate the signal. The wires 4 which are connected with the electric lights extend to the operating devices and as each operating device is constructed in the same manner, a description and illustration of one of the operating devices is deemed sufficient. The signal may be supported in any desired manner and may be of any desired dimensions.

Each signal operating device comprises in its construction a base member 5 designed to extend longitudinally of a portion of a railroad track and secured to the adjacent rail by means of transverse bolts 6 which preferably pierce the flap of the adjacent rail but any other suitable means may, of course, be employed for securing the base member 1 to the rail. The base member 1 is provided with a central recess 7 in which is arranged a switch 8. The switch 8 is similar in construction to an ordinary snap wall switch and is provided with a pair of depressible buttons 9 and 10 which are adapted to be pushed downwardly or inwardly in the ordinary manner for closing the circuit and for opening the same to light the electric lamp and to extinguish the same. As the switch is of the ordinary construction and operates in the ordinary manner and as any desired construction of snap switch mechanism having a pair of depressible buttons may be employed the specific construction of the switch is neither illustrated nor described. The switch is secured to a switch operating device consisting of an oblong plate 11 provided with a pair of cylinders 12 and 13 adapted to receive the push buttons 9 and 10 of the electric switch. The switch is provided with projecting ears 14 which are of the ordinary construction and which are secured to the lower or inner face of the plate by bolts 15, suitable insulation 16 being interposed between the box or casing of the electric switch and the plate 11 which is constructed of suitable metal. The cylinder 13 is open at the upper or outer end and it receives a plunger 17 which rests upon the push button 9 and which is adapted to be depressed by the means hereinafter described for moving the push button 9 downwardly or inwardly to close the circuit and illuminate the signal by causing the electric light to glow. The plunger is provided at its inner end

with an annular rib 18 and a cylinder is provided near its upper outer end with an interior annular shoulder 19 which forms a stop for limiting the upward or outward movement of the plunger 17. The cylinder 12 which is closed at its outer end 20 contains a coiled spring 21 provided at its lower end with a flanged collar 22 which caps the depressible push button 10 of the electric switch and when the push button 9 is depressed the push button 10 is moved forwardly and effects a compression of the spring 20. When the plunger 17 is relieved of the pressure the spring 20 expands and forces the push button 10 downwardly and automatically opens the circuit and extinguishes the electric light of the signal. The plate 11 is secured by bolts 23 to the base member recesses 24 being provided at opposite sides of the central opening or recess 7 to receive the plate 11 which is arranged in flush relation with the upper face of the base member.

The base member is provided at opposite sides of its center with fixed upwardly projecting guides 25 consisting of posts which are preferably formed integral with the base member. The base member may be constructed of any suitable material and the spaced vertical guides fit in openings 26 of a depressible member 27. The depressible member 27 is constructed of metal or other suitable material and it is preferably provided with integral side and end flanges and it partially encases the base member. The depressible member is beveled at its ends at 28 as shown and it is yieldably supported in an elevated position above the thread of the adjacent rail by means of coiled springs 29 which may be of any desired number. The coiled springs are disposed on bolts 30 which may be formed integral with the depressible vehicle member and they pass through openings 31 in the base member. The bolts 31 are provided with nuts at their lower ends and the base member is recessed at its lower face at 32 to receive the said nuts. The bolts 29 may be formed integral with the depressible member and when the wheels of a train pass over the depressible member the latter is forced downwardly and it carries with it the plunger 17 of the cylinder 13 for operating the switch to illuminate the signal. The depressible member may be of any desired length and the form of the same may be changed to adapt it for use at any location either for the railroad or at a highway to be depressed by the wheels of an automobile or other vehicle. In practice when the device is used at a railroad crossing the operating means will be depressed by a train approaching the crossing and the wheels of the train passing over the depressible member will cause an intermittent illumination of the signal and

a flaring of the same so that attention will be attracted to the signal. Any number of the operating devices may be employed for producing an illumination of the signal by a train any desired distance from the crossing and until the train has reached and passed the crossing. The wires 4 of the lamp circuit extend to the electric switch and are connected with the same in the usual manner and any suitable source of electric current supply such as a battery or feed wires of an electric lighting system may be employed for supplying the current to the lamp circuit of the signaling device.

In order that the depressible member may move frictionlessly the base member may be provided with suitable anti-friction bearings which may consist of balls 33 mounted in suitable sockets 34 of the base member and projecting slightly therefrom at the ends of said base member to bear against the depressible member or any other suitable anti-friction bearings may be employed.

What I claim is:

1. An electric signal including a signal circuit, a switch arranged in the said circuit and provided with a pair of depressible push buttons, a switch operating device comprising a pair of cylinders, adapted to receive the depressible push buttons, a plunger mounted in one of the cylinders and projecting therefrom and arranged to actuate one of the push buttons, and a coiled spring mounted in the other cylinder and arranged to be compressed by the other push button for automatically actuating the switch to open the circuit when the plunger is relieved of pressure and operating means adapted to be actuated by a vehicle for depressing the plunger.

2. An electric signal including a signal circuit, a switch arranged in the said circuit and provided with a pair of depressible push buttons, a switch operating device comprising a pair of cylinders arranged to receive the push buttons, one of the cylinders being closed at its outer end and the other being open, a plunger projecting from the open end of the cylinder and arranged to actuate one of the push buttons, a spring housed within the other cylinder and interposed between the closed end thereof and the other push button and adapted to be compressed by the same when the plunger is operated to close the circuit and adapted to automatically open the circuit when the plunger is relieved of pressure and operating means adapted to be actuated by a vehicle for actuating the plunger.

3. An electric signal including a signal circuit, a switch arranged in the said circuit and provided with a pair of depressible push buttons, a switch operating device comprising a pair of cylinders arranged to receive the push buttons, one of the cylinders being

- closed at the outer end and the other cylinder being open and having an interior shoulder, a plunger projecting from the open end of said cylinder and arranged to actuate one of the push buttons and provided with a lip arranged to engage the said shoulder to limit the outward movement of the plunger, a coiled spring housed within the other cylinder and interposed between the closed end thereof and the other push button and provided with a flanged collar capping such push button and operating means adapted to be engaged by a vehicle for actuating the plunger.
5. An electric signal including a base member having a central opening and provided with fixed guide posts located at opposite sides of the center of the base member, a compressible member adapted to be engaged by the wheels of a vehicle and provided with openings receiving the guide posts, cushioning means interposed between the base member and the compressible member, a switch mounted in the central openings of the base member and arranged in the said circuit and
- switch operating means carried by the base member and arranged to be engaged by the compressible member.
5. An electric signal including a base member provided with a central opening and having recesses at opposite sides thereof, a switch located in the said opening and having a pair of compressible push buttons, a plate spanning the opening of the base member and secured to the same at opposite sides of the said openings and carrying the said switch, cylinders mounted on the plate and receiving the push buttons, a spring arranged within one of the cylinders and adapted to be compressed by the operation of the switch, a plunger extending from the other cylinder and arranged to engage the other push button, and a yieldably supported compressible member mounted on the base member and arranged above the plunger and adapted to be operated by a vehicle for actuating the plunger.

In testimony whereof I have hereunto set my hand.

BRUCE J. SHALD.
